DEVICE FOR SETTING CARBURETOR FLOATS

Theodore J. Baas, Westbrook, Minn.

Application August 9, 1950, Serial No. 178,442

1 Claim. (Cl. 33—180)

1

The present invention relates to a device for setting carburetor floats and it consists in the combinations, constructions and arrangements of parts herein described and claimed.

Generally there is provided a device for setting the floats of conventional carburetors and it consists of a substantially L-shaped body having a vertically extending portion which is marked with indicia measuring the distance from the horizontally extending portion and such vertically extending portion is threaded from the bottom upwardly throughout approximately one half of its length. Novel means is provided for mounting thereon a horizontally extending swingable arm which is normally urged in a downward position against a threaded follower by means of a compression spring surrounding the vertical member and bearing against a washer at the upper end of the vertical member which washer is held in position by means of the handle or horizontally extending portion of the body. A novel means is provided for turning the follower upon the body.

It is accordingly an object of the invention to provide a device of the character set forth which is simple in construction, inexpensive to manufacture and yet effective and efficient in use.

Another object of the invention is the provision of a device of the character set forth having a novel follower and novel means for operating the same.

A still further object of the invention is the provision of a novel swingable arm and mounting therefor, such arm and mounting both forming parts of the invention.

Other and further objects of the invention will become apparent from a reading of the following specification taken in conjunction with the drawing, in which:

Figure 1 is a side elevational view of an embodiment of the invention.

Figure 2 is an end elevational view of Figure 1.

Figure 3 is a side elevational view of one element of the invention shown in Figures 1 and 2.

Figure 4 is a sectional view taken along line 4—4 of Figure 1.

Figure 5 is a sectional view taken along line 5—5 of Figure 1, and

Figure 6 is an isometric view of another element of the invention as shown in Figures 1 and 2.

Referring more particularly to the drawing, there is shown therein a substantially inverted L-shaped body comprising a horizontally extending handle 10 and an integrally formed vertical member 11 the lower half of which is threaded, as indicated at 12, and one side of which is flattened, as indicated at 13. The flattened portion 13 is provided with indicia 14 which indicia denotes the distance from the underside of the handle 10 to the underside of an arm 15 which is formed integrally with a U-shaped clamp member 16 having its bight portion bifurcated as shown at 16a to provide a pair of outstanding ears 17 through which a bolt 18 extends. The bolt 18 is provided with a nut 19.

The clamp member 16 is substantially U-shaped and surrounds the vertical member 11 and has interposed between its arms a collar 20 which likewise surrounds the vertical member 11.

A washer 21 is mounted upon the member 11 and abuts the upper end of the clamp member 16 while a washer 22 likewise mounted upon the vertical member 11 abuts the underside of the handle 10. A compression spring 23 likewise surrounds the member 21 and is adapted to bear against the washer 21 at one end and the washer 22 at its other end.

A washer 24 is also mounted upon the member 21 and abuts the underside of the arm 15. A follower 25 is threadably mounted upon the threaded portion 12 of the member 11 and is provided with an outstanding lever 26.

In operation, it will be apparent that in order to ascertain whether or not a proper float adjustment is extant in a carburetor, the follower 25 is first adjusted by means of the lever 26 until the indicia 14 give a proper reading. Whereupon the nut 19 may be tightened upon the bolt 18 to thereby maintain the arm 15 in latched position, if desired upon the member 11. Thereafter the handle 10 is rested upon the carburetor bowl and the arm 15 may then be used to test the correct height of the float, it being understood that if the float is correctly positioned, the arm 15 will just clear the same and if not correctly positioned, the same must then be adjusted until the arm 15 does barely clear the float.

While but one form of the invention has been shown and described herein, it will be readily apparent to those skilled in the art that many

minor modifications may be made without departing from the spirit of the invention or the scope of the appended claim.

What is claimed is:

A device of the character described comprising 5 a vertical body member having indicia thereon, an integrally formed horizontally extending handle at the upper end of said body, a clamp member vertically slidable and revolvably mounted on said body, a follower threadably mounted upon 10 the lower portion of the body below said clamp member, an arm formed integrally with said clamp member and extending in spaced parallel relation to said handle, a compression spring surrounding the upper portion of said body and 15 urging said clamp member against said follower, and a nut threadably mounted on said body below said clamp.

THEODORE J. BAAS.
